UNITED STATES PATENT OFFICE.

FRANCIS C. HABER, OF BROOKLYN, NEW YORK.

FEED-WATER PREHEATER.

Application filed November 26, 1926. Serial No. 150,683.

This invention relates to a new and useful device in the nature of a feedwater preheater particularly adapted for use in connection with steam boilers for the purpose of pre-heating the feedwater supplied to a steam boiler.

An object of the invention is to provide a feedwater preheater which will increase the efficiency of the steam boiler.

10 A further object of the invention is to provide a feedwater preheater of novel construction and arrangement of parts, hereinafter more fully described, claimed and illustrated in the accompanying drawings, in which:

15 Fig. 1 shows a front elevational view of a steam boiler, partly in section, seen as though looking as indicated by the line 1—1 in Fig. 2, and equipped with my improved feedwater preheater.

20 Fig. 2 shows a vertical longitudinal sectional view taken on the line 2—2 of Fig. 1.

Fig. 3 shows a perspective detail view of my improved feedwater preheater.

Fig. 4 shows an enlarged sectional view 25 taken on the line 4—4 of Fig. 3.

Fig. 5 shows a further development of my improved device.

Fig. 6 shows an enlarged sectional detail 30 view of the valve for regulating the supply of feedwater.

The shell proper 10, the upper shell members 11, 12, 13 and 14, attached thereto in the usual well known manner, the fire box 15, grate bars 16, fire doors 17, the tubes 18 and ash pit 19 are the common elements of a fire tube boiler such as ordinarily employed to generate steam. It should be understood that I do not limit the use of my invention to steam boilers of the type above referred to 40 and described, but to all classes and types of steam boilers such as generally manufactured and used.

As here embodied my improved device comprises a water inlet pipe 20, leading from any 45 convenient source of supply, controlled by a valve 21, the pipe passing through the upper shell member 13 to enter the central lateral opening of an ordinary commercial T fitting 22. In the end openings of the T fitting 22 are engaged elbows 23, having their opposite ends directed horizontally and in which are fixed pipes 24 leading to return elbows 25. Return pipes 26 engage in the other openings of the return elbows 25 and extend parallel below the same horizontal

plane to connect with the return elbows 27. Similar return pipes 28 engage in the other openings of the return elbows 27 and extend parallel below the same horizontal plane to connect with the elbows 29. In the opposite 60 openings of the elbows 29 are engaged nipples 30, which engage with the valve casings 40. In the coating openings of the valve casings 40 are engaged the pipes 32 disposed in parallel below the pipes 28. The pipes 32 are 65 provided with caps 33, and contain a plurality of relatively small perforations 34, located or positioned in the upper half portion of the pipes 32.

In order to support this structure, clips 35 70 are secured to the stay rods 36 carried by the upper shell members 11 and 12, and to the pipes 24, 26, 28 and 32, maintaining my improved device at any preferred height within the space at the top of the steam boiler, so 75 as to permit the pipes 32 to be somewhat below the water level.

In operation, steam being generated in the boiler fills the space above the water line and imparts a portion of its heat to my improved 80 device suspended therein. If the valve 21 be opened permitting the inlet of feedwater, the same flows through the pipes and fittings arranged symmetrically on each side and eventually escapes through the perforations 85 in fine spray at a high temperature and adds to the supply of water already in the boiler.

Referring in particular to Fig. 5 of the accompanying drawings, the above mentioned inlet pipe 20 enters the central lateral 90 opening of an ordinary commercial flanged T fitting 37. In the end openings of the flanged T fitting 37 are engaged the elbows 23 and similar elbows 38, of somewhat smaller size or dimensions, so as to permit a second 95 pair of the above described structures to be attached thereto, as would be advantageous in boilers of larger size.

The valve casings 40 are supported to the shell proper 10. The pipes 32 are provided 100 with internal threads 41, at their extremities adjacent to the valve housings 40, adapted to receive the valve proper 42, integral with or attached to the valve stem 43, having a hand-wheel 44 attached thereto, positioned 105 outside the shell proper 10. The extremities of the pipes 32, adjacent to the valve housing 40, are provided with elongated slots 45, which register with the nipples 30, said registering being maintained by the threaded 110

member 46, a set screw or the like, positioned in threaded apertures of the valve housing 40 and the pipes 32. The apertures 47 are located in the valve proper 42. A packing gland 48, threadedly attached to the valve housing 40, is provided, to hold the packing 49 in place, so as to prevent leakage of the feedwater.

The above described construction is such as will permit the valve proper 42, when turned or rotated by the hand-wheel 44, to regulate the amount of feedwater supplied to the steam boiler. It should be understood that the apertures 47 in the valve 42 are adapted to permit a predetermined amount of water to flow into the pipe sections 32 when the valve is positioned to the right as viewed in Fig. 6. These apertures thus provide for the passage of a minimum amount of water into the pipe extension 32 at all times and when it is desired to increase the supply of water to the boiler, the valve 42 may be moved to the left as viewed in Fig. 6 so as to uncover the slot 45 and permit a direct communication between the nipple 30 and the extension 32. It should also be understood by controlling or regulating the flow of water at the lowermost part of the system, it is possible to regulate not only the amount of water that is discharged into the boiler, but the length of time such water is retained in the uppermost portion of the feed system

where it is subject to the heat of the steam developed in the boiler.

Having thus described my invention, what I claim as new and desire to protect by Letters Patent of the United States is as follows:

A preheater for steam boiler feedwater comprising an upper series of imperforate pipes disposed above the water level of said boiler adapted to convey feedwater therethrough for allowing the same to be heated, a pipe extension disposed below the surface of the water in said boiler and communicatively connected with said series of pipes having perforations therein adapted to discharge feedwater into said boiler below the surface of the water therein, a valve casing forming the connection between said upper series of pipes and said pipe extension, said pipe extension being disposed at one end in said valve casing and screw threaded internally at said end portion, a valve in said casing having apertures therein for permitting a predetermined minimum amount of water to flow from said series of pipes to said extension and actuating mechanism operatively connected with said valve for adjusting the position of the same for regulating the flow of liquid to said pipe extension above said predetermined amount.

In testimony whereof I have affixed my signature.

FRANCIS C. HABER.
